DUST SHIELD FOR MATERIAL SPREADING DEVICE

Roy C. Gaddis, Cedar Rapids, Iowa

Application October 11, 1949, Serial No. 5,419

Term of patent 14 years

(Cl. D35—1)

To all whom it may concern:

Be it known that I, Roy C. Gaddis, a citizen of the United States, residing at Cedar Rapids, State of Iowa, have invented a new, original, and ornamental Design for Dust Shield for Material Spreading Device, of which the following is a specification, reference being had to the accompanying drawing, forming a part hereof.

Figure 1 is a rear view in perspective illustrating my design for dust shield for material spreading device, as it appears when mounted on the rear end of a material spreading truck, the truck and fabric curtains depending from the dust shield being indicated in dotted lines and shown only for illustrative purposes.

I claim:

The ornamental design for a dust shield for material spreading device, as shown and described.

ROY C. GADDIS.
